(57) **CLAIM**

I claim the ornamental design for a wheel for a barbecue, as shown and described.

DESCRIPTION

FIG. 1 is a top perspective view of a wheel for a barbecue showing my new design;

FIG. 2 is a top plan view thereof;

FIG. 3 is a front elevational view thereof;

FIG. 4 is a right side elevational view of FIG. 3;

FIG. 5 is a left side elevational view of FIG. 3;

FIG. 6 is a rear elevational view thereof;

FIG. 7 is a bottom plan view thereof; and,

FIG. 8 illustrates the wheel for a barbecue in its environment which is shown in broken lines and which forms no part of my design.
